UNITED STATES PATENT OFFICE.

NICHOLAS P. KOSTECK, OF PITKIN, COLORADO.

COLLAPSIBLE CRATE.

1,358,562.

Specification of Letters Patent. Patented Nov. 9, 1920.

Application filed August 30, 1918, Serial No. 252,090. Renewed May 24, 1920. Serial No. 383,924.

To all whom it may concern:

Be it known that I, NICHOLAS P. KOSTECK, residing at Pitkin, in the county of Gunnison and State of Colorado, have invented 5 new and useful Improvements in Collapsible Crates, of which the following is a specification.

This invention relates to a collapsible crate, and one object is to produce a receptacle 10 of the character indicated which shall be especially adapted for use in the display of fruit, vegetables and other food products and which may also be employed for shipping certain articles by parcel post or otherwise.

A further object is to provide a receptacle comprising a bottom member, a plurality of hinged end members, a hinged front member and a member similarly formed constituting 20 the rear wall of the crate, a folding top being hinged to the said rear wall of the crate, and a foldable partition member dividing the crate into a plurality of compartments, this member last named extending 25 preferably midway between the ends of the device.

A still further object is to provide certain novel means whereby the folding and collapsing elements may engage adjacent 30 elements when the crate is set up, and certain novel means for effecting the hinge connection at various portions of the device.

With the foregoing and other objects in view, the invention consists in the novel construction, combination and arrangement of elements hereinafter described and claimed:

In the drawings,

Figure 1 is a view in side elevation.

Fig. 2 is a top plan view.

40 Fig. 3 is a top plan view of the collapsed crate.

Fig. 4 is a side view of the collapsed crate.

Fig. 5 is an end view.

45 Fig. 6 is a transverse vertical section, with the central partition member in elevation.

In carrying out my invention, I employ a bottom member designated 10 and comprising a plurality of side bars 11 and 12, the latter being connected at points midway 50 between the ends by a transverse bar 13 with which a middle partition wall 14 is connected. Bar 13 passes loosely through end portions 15 of partition 14.

Each side bar 11 and 12 of the bottom is 55 provided with an upstanding member at the respective ends thereof, these elements being

preferably formed by deflecting the bars 11 and 12 from a horizontal to a vertical position. The bottom further includes bars 17 and 18 extending across the ends. 60

The end frames each include vertical bars 20 and 21 pivotally connected at 22 with the upstanding members previously referred to and formed on elements 11 and 12. A bar 24 extends transversely of each end frame 65 at the point of pivotal connection 22 and an upper bar parallel with bar 24 connects the side elements 20 and 21 of the end frames and is designated 25. These bars 25 form tie rods, the upper bars of the end frames 70 being formed integrally if desired with the side bars 20 and 21. The upper bar is designated 26 and connected therewith is a handle 27. Each end frame is similarly formed.

The front and rear frame members 75 mounted on the elements 11 and 12 of the bottom each comprise an upper longitudinal bar 30 vertical end bars 31 and 32 and a lower tie rod 33, the latter passing through ears 34 and 35 upon the front bar 12 of the 80 bottom and forming a pivotal connection for the front and rear frames.

The front and rear frames each carry at 85 their upper corners certain devices of hook formation extending laterally and adapted to engage the upper bars 26 of the end frames, the engagement being from the under side of said bars 26. The vertical bars of the end frames are deflected at 38, permitting the hook members 36 to be moved 90 into position without engaging the transverse bars 25 of the end frame.

The top of the crate comprises a plurality of end members, each of which comprises two elements 40 and 41 pivotally connected at 42; a central longitudinal connecting rod 43 passes through the point of pivotal connection and serving in part to effect such connection. Each end of the rod 43 is provided with an engaging device 44 of 100 hook formation and adapted to engage the under side of bars 26 of the end frames. The top further includes longitudinal bars 45 and 46, the front bar 46 carrying an apertured member 47 engaged by the locking 105 device mounted on the upper bar 30 of the front frame member. This locking device may be of any desired type but is here shown as comprising a thumb screw 45' passing through a nut 48 mounted in a 110 downwardly deflected portion 30'. The screw also passes through the apertured

portion 47 and is engaged by a wing nut 48'. Nut 48 is provided with a slot 50 in one side thereof, and a similar slotted device 51 is located on the upper bar of the rear frame member. The central vertical partition member engages the slotted devices when thrown to its operative position.

The several frame members, or any of them, may be covered with wire mesh. Any 10 one of these frame members may, however, be covered with sheet metal or the like if desired.

In collapsing the crate the end members are sprung outwardly to a given extent, 15 permitting the front and rear frames and the top to clear the end frames. The front and rear frames are folded toward each other and the top is then folded over the rear frame. Finally the end frames are 20 folded toward each other, and the crate assumes its most compact form. It is of course understood that the middle partition member is the first element collapsed.

What is claimed is:

25 1. In a device of the class described, a bottom frame comprising a plurality of parallel bars forming longitudinal elements of the frame, bars connecting the ends of the longitudinal elements, upstanding devices carried by the said longitudinal elements, end frames pivotally connected to the upstanding devices, front and rear frames each comprising vertical end bars and a horizontal upper bar, ears carried by the 30 parallel bars of the bottom frame near the

ends thereof, a rod connecting the vertical bars of the front and rear frames and effecting pivotal connection with the aforesaid ears, engaging devices projecting from the upper corners of the front and rear frames and engaging the upper bars of the end frames from the under side thereof, a middle partition member and means for hingedly connecting the latter with the bottom frame and for detachably connecting 40 the middle partition with the front and rear frames, and a collapsible top frame hingedly connected with the upper portion of the rear frame.

2. In a device of the class described, a 50 bottom frame including upwardly deflected ends, front and rear frames hingedly connected with the bottom frame, end frames hingedly connected with the deflected ends of the bottom frame, engaging devices 55 formed on the upper corners of the front and rear frames and comprising hook members engaging the upper elements of the end frames on the under side thereof, a top hingedly connected with the rear frame and comprising end bars formed in a plurality of sections pivotally connected, a central longitudinal connecting bar effecting the aforesaid pivotal connection, hook members 60 carried by the ends of the central longitudinal bar and positioned to engage the upper elements of the end frames aiding in retaining the latter and in retaining the cover.

In testimony whereof I affix my signature.

NICHOLAS P. KOSTECK.
